(57) **CLAIM**

The ornamental design for a playground seat, is shown and described herein.

DESCRIPTION

FIG. 1 is a perspective view of a seat design;

FIG. 2 is a top elevational view thereof;

FIG. 3 is a front elevational view thereof; the backside being a similar image thereof;

FIG. 4 is a bottom image thereof; and,

FIG. 5 is a left side elevational view thereof; the right side being a mirror image thereof.

The broken lines are for illustrative purposes only and form no part of the claimed design.
